UNITED STATES PATENT OFFICE

MEAD HEDGLON, OF SYRACUSE, NEW YORK

PORTABLE IRONING MACHINE

Application filed November 17, 1927. Serial No. 233,906.

This invention relates to portable ironing machines, such as are commonly used in homes and various institutions, and the invention has especial reference to the improvement of the devices shown and described in my United States Patents No. 1,560,990, November 10, 1925, and No. 1,636,472, July 19, 1927.

Briefly, the ironing machine comprises a motor driven padded ironing roll, which rotates in a fixed horizontal plane, and a heated upwardly facing trough-like shoe, in which the roll rotates, and moves the articles frictionally over the surface of the trough. The rear side of the shoe is supported preferably by links, and the forward side is resiliently and adjustably supported for movement towards and away from the roll, the said movements heretofore being usually controlled by a hand-lever. In my former patents these resilient supports for the shoe normally rest upon the platform or base, that supports the whole of the ironing mechanism, and any vertical movements of the shoe are necessarily limited, and can only be effected by the manipulation of the hand-lever. It has been found that, in order to separate the roll and shoe, for the purpose of recovering or adjusting partially ironed articles, that are liable to become distorted or imperfectly ironed if allowed to continue through the machine, the operator must either shut off the power, and manually lower the shoe, or else simply throw the hand-lever in the direction for separating the shoe from the roll, readjusting the articles, and then operating the hand-lever again to restore the shoe to the ironing position. This leaves but one hand free to adjust and guide the articles, and necessarily causes more or less waste of time and tends to wear out vital parts of the machine.

In the present case, the resilient supporting means may be suitably adjusted in advance of an ironing operation, for yielding the desired ironing pressure, and this adjustment need not be disturbed during the ironing period, unless the work calls for variations of the ironing pressure. To accomplish this result, and at the same time enable the operator to readily and quickly recover

and adjust any article that is partially ironed, I provide a pedal or like means controlled by the operator's feet, by which the shoe may be lowered in case of emergency, thereby enabling operator to employ both hands for adjusting the articles, the said pedal and related parts being arranged to effect the raising of the shoe again to the ironing position without disturbing the adjustment of the parts that control the pressure, and without necessitating the stoppage of the ironing roll, or requiring the power to be either turned on or off. To this end, I provide a rocking shaft that is equipped with levers upon which the resilient supports for the forward side of the shoe are mounted. This shaft is arranged to be rocked for lowering and raising the shoe, by an eccentric mechanism, which may be set in motion instantly by a clutch that is controlled solely by the pedal. The clutch is released automatically when the foot pressure is relaxed, by tension means which effects the stoppage of the eccentric mechanism.

The various features and parts of the invention will be understood from the detailed description which follows, and by reference to the accompanying drawings, in which—

Figure 1 is a broken front side elevation of the ironing machine, showing the pedal-controlled eccentric mechanism in relation to the other parts when they are in the ironing position. Fig. 2 is a front end elevation of the same. Fig. 3 is an enlarged end view of the gear-box, with the cover removed, showing the motor-driven gear-train that operates the press-roll. Fig. 4 is a vertical cross-section, taken on line 4—4 of Fig. 5, showing the shoe lowered from the roll by the action of the eccentric. Fig. 5 is a broken vertical longitudinal section, taken on line 5—5 of Fig. 2, showing the eccentric and related parts in the operative positions, shown in Fig. 4. And Fig. 6 is a top plan view of the table, with some parts omitted, showing the oblong open frame, the brace that supports the pedal, and the ironing parts.

In the drawings, 2 represents a table whose top comprises a normally open frame 2' that is supported at its four corners by legs 2^a, the latter preferably being equipped with castors.

2^b. The top portion of the table and the corresponding portions of the legs are enclosed and braced by sheet metal or other skirting 2^c, and the lower ends of the legs are stiffened by 5 an X-shaped brace 2^d, which parallels the frame. (See Figs. 1, 2 and 6.) The opposite long sides of the frame are usually fitted with foldable leaves 2^e, which are hinged to the frame at 2^f. 3 represents an oblong wooden 10 or other base, which supports the whole of the ironing mechanism. The base 3 is preferably loosely disposed in the opening of the frame 2^e and may be held therein by hinges or by any suitable means (not shown). The 15 base 3 is preferably removable for facilitating applying and adjusting the various mechanical parts.

The ironing machine comprises a padded press roll 4, which is mounted on a shaft 4', one end of the latter being journaled in a 20 goose-neck bracket 5, which is rigid to the base 3, the opposite end of said shaft being supported by an upright gear-box 6, having an open side 6', which is closed by a cap or 25 cover 6^a. The roll 4 is preferably driven by an electric motor 7, whose armature shaft 7' extends into the gear-box and supports and drives a worm 7^a, that meshes and drives a worm-gear 7^b, which is mounted loosely on a 30 normally idle shaft 8. One side of the worm-gear supports and drives a pinion 8' that meshes and operates a spur-gear 9, which is loose on the shaft 4'. The opposite side of gear 8 is formed with a hub 8^a, which 35 comprises one member of a clutch. The gear 9 is formed with a similar hub comprising a clutch member 9', which is arranged to be interlocked with a clutch-sleeve 9^a, the latter being keyed to shaft 4', as at 9^b, and drives the 40 roll 4 when the clutch members 9'-9^a are engaged, as shown in Fig. 5. The roll 4 may be stopped at any time by the disengagement of the clutch 9'-9^a by a handle 9^c. The ironing is effected by the roll 4, moving the articles frictionally over a heated surface of a 45 shoe 10. The shoe comprises a hollow body formed with an upwardly facing trough-like surface, which is disposed concentrically beneath the roll, the rear side of the shoe being 50 supported swingably by a pair of links 12, which are pivoted respectively to the shoe and the base 3, as shown in Fig. 4. The forward side of the shoe 10 is resiliently supported at its opposite ends, by springs 13, and rods 13' 55 that telescope the springs, the said rods being threaded, and the tension being controlled by means of nuts 13^a. The upper ends of the rods 13' are fitted with eccentric devices 13^b, which are pivoted to the ends of the shoe, as 60 at 13^c, one of said devices supporting a hand-lever 13^d, by which the shoe may be manually raised and lowered relatively to the roll 4. The shoe is usually heated electrically, in the well-known manner, but the means is not 65 shown in the drawings. The articles are sup-

ported, while being fed between the roll and the shoe, by a table or shelf 14. The springs 13 and the lower ends of the rods 13' pass through openings in the base 3, and the rods are fitted with clevises or forks 13^e, which are 70 pivoted to forwardly extending levers or arms 15' carried by a rock-shaft 15, the latter being journaled in bearing lugs 15^a secured to the underside of the base 3, as shown in Figs. 1 and 4. The shaft 15 is also equipped 75 with a rearwardly extending lever 15^c, to which is pivoted the lower end of a rod 16' that depends from a circular casing 16, in which is rotatably disposed an eccentric disk 17, the latter being rigid on a reduced end of 80 the shaft 8, upon which the worm-gear 7^b normally loosely rotates. The eccentric 17 is operated for lowering and raising the shoe, by the clutch member 8^a, which is integral with the gear 7^b, and another member 18, the 85 latter being spool-shaped and being keyed to the shaft 8, as at 18', by means of which said shaft is rotated when said members are engaged, as shown in Fig. 5. Between its flanges 18^a, the member 18 is formed with a 90 tooth or cam 18^c, which is arranged to be engaged by the upper end of a bolt 19, which is reciprocatable in a housing 19' of the cap 6^a. The lower end of the bolt 19 connects with a flexible pull-rod or chain 20, which extends downwardly through an opening in the base 3, and connects with an arm 21' of a 95 pedal 21. The depressing of the pedal correspondingly moves the bolt 19 clear of the path of the cam 18^c, and enables a spring 18^d to throw the member 18 into engagement with the motor-driven gear 7^b. The bolt 19, as well as the pedal 21, are moved upwardly, for causing the bolt to release the clutch member 18, by a spring 19^a, which is disposed in 100 the housing 19'. The pedal 21 is pivotally mounted between depending lugs 21^a, which are supported by the brace X, as shown in Figs. 1 and 2, in which the full lines show the pedal and related parts released, for enabling the shoe 10 to resume the ironing position, shown in Figs. 1 and 2. The dotted position of the pedal in Fig. 2, corresponds to the full line position of the bolt in Fig. 5, which enables the clutch 8^a-18 to operate the 110 eccentric disc 17 and rock shaft 15 for the emergent lowering of the shoe 17, as shown in Fig. 4. In order to enable the operator to raise and lower the shoe 10, by the manipulation of the hand-lever 13^d, without hindrance from the eccentric 17 and related parts, the free ends of levers 15' are preferably slotted, as at 15^d (see Fig. 4). By this arrangement clevis pins 13^e are enabled to slide sufficiently to overcome the resistance of 120 the said parts. The pedal 21 is preferably of such length as to enable the operator to readily and conveniently operate the eccentric 17 with either the right or left foot, without requiring any shifting of his body. 130

Having thus described my invention, what I claim is—

1. In combination with an ironing roll, a shoe cooperating with said roll, means depending from the rear of the shoe to pivotally mount same, a rock shaft underlying the shoe, a resilient device pivoted to and depending from the front of the shoe, means to connect said device to the rock shaft, an eccentric device connected to the rock shaft, power means to drive the roll, means to operate the eccentric device from the power means thereby to move the shoe away from the roll, and foot actuated means to operate the means for operating the eccentric device. 15
2. In combination with an ironing roll, a shoe cooperating with said roll, means depending from the rear of the shoe to pivotally mount same, a rock shaft underlying the shoe, a resilient device pivoted to and depending from the front of the shoe, means to connect said device to the rock shaft, power means to drive the roll, and foot controlled means to actuate the rock shaft from the power device. 20
3. In combination with an ironing roll, a shoe cooperating with the roll, means to mount the shoe for movement toward and away from the roll, a shaft, an eccentric on the shaft, means to operate the shoe by the eccentric, power means for operating the roll and the shaft, a clutch on the shaft, a spring held compressible bolt to normally engage the clutch and hold same inoperative, and foot actuated means connected to the bolt to depress same and render the clutch operative. 25
4. In combination with an ironing roll, a horizontal shaft adjacent an end of the roll, a clutch on the shaft, power means to operate the shaft, means to operate the roll from the shaft, a shoe, means to mount one side of the shoe for movement toward and away from the roll, a horizontal rock shaft, radial arms on the shaft, a connection depending from the opposite side of the shoe and connected to one of said arms, means connected to the first named shaft and to the other arm for operating the shoe, and foot operated means for actuating the clutch. 30
5. In combination with a base and an ironing roll, a shoe cooperating with said roll, means depending from the rear of the shoe and pivoted thereto and to the base to mount the rear of the shoe, a rock shaft underlying the shoe, a resilient device depending from the front of the shoe, an arm fast on the rock shaft, means to pivotally connect the resilient device to said arm, manually controlled means pivoted to said device and to the shoe for operating the latter, means for adjusting the tension of the resilient device thereby to vary the ironing pressure and means to operate the rock shaft. 35
6. In combination with a base and an iron- 65
- ing roll, a shoe cooperating with said roll, means depending from the rear of the shoe and pivoted thereto and to the base to mount the rear of the shoe, a rock shaft underlying the shoe, a resilient device depending from the front of the shoe, an arm fast on the rock shaft, means to pivotally connect the resilient device to said arm, manually controlled means pivoted to said device and to the shoe for operating the latter, a second arm on the rock shaft, means actuated by the second arm for operating the shoe, and foot controlled means for actuating the rock shaft. 70
